OSCILLOGRAPH GALVANOMETER

Marvin E. Morrow, Tulsa, Okla., assignor to Mid-western Geophysical Laboratory, Tulsa, Okla., a corporation of Delaware

Application September 11, 1950, Serial No. 184,156

3 Claims. (Cl. 324—154)

1

This invention relates to electrical devices for measuring currents or voltages and particularly adapted for use in connection with instruments for producing visual or photographic records of voltage or current changes. Oscillograph cameras employed in the field of geophysics are usually provided with a bank of moving coil galvanometers each of relatively small nature requiring delicate manufacturing operations that normally render the cost of production relatively great.

There is accordingly a need by seismologists especially for an inexpensive, positively operating and long-lasting galvanometer that is capable of withstanding considerable abuse under various types of operating conditions.

It is one of the important objects of this invention therefore, to provide a galvanometer having a coil mounting securing means that will effectively maintain the mirrors of the instrument in a set position while the securing means manipulated to the locked condition; having high resistance to corrosion; and of such nature as to present a positive, tight fit against entrance of the elements, such as dust and moisture, into the coil housing.

Another object of the instant invention is to provide a galvanometer having a novel coil mounting assembly formed to progressively increase its sealing function as pressure is applied thereto and to maintain such seal during the time the instrument is in use, all without altering the pre-set position of the mirror with respect to the window of the device.

A further object of the invention hereof is to present a combination mounting and closure assembly that is readily releasable even after considerable use under normally damaging operating conditions.

A still further object of this invention is to provide an assembly as above set forth that is less expensive than heretofore provided by virtue of reduction in cost of materials.

In the drawing:

Figure 1 is a substantially central, longitudinal sectional view of an oscillograph galvanometer made pursuant to my present invention.

Fig. 2 is an enlarged, fragmentary, sectional view taken on line II—II of Fig. 1; and

Fig. 3 is a cross-sectional view taken on line III—III of Fig. 2.

An elongated, hollow housing 4, of any suitable non-magnetic material is provided intermediate the ends thereof with a pair of opposed pole members 6 and 8. In normal use, the bank

2

of galvanometers are mounted in a magnet assembly (not shown) and each fits within an opening with members 6 and 8 disposed between a pair of pole elements forming a part of the assembly. Electrical connection with the coil of the assembly is made through a conductible lock nut 10 at one end of the housing 4.

A movable coil 12 is held between the members 6 and 8 by a pair of opposed conductors 14 and 16, conductor 14 being secured to a spring 18 and conductor 16 having soldered attachment with head 20 of a mounting broadly designated by the numeral 22.

Spring 18 is carried by a polygonal, non-rotating reciprocable block 24 having ball and socket connection 26 with a threaded plug 28. Screw 28, as well as a threaded closure 30, are received by housing 4 by virtue of the latter being tapped as at 32 and a lock screw 34 holds block 24 in an adjusted position. The vibrations of conductor 14 induced by coil 12 are rendered visible through a transparent panel 36 forming a part of housing 4. Mirror 37 is mounted on coil 12 in the conventional manner.

Internal threads 38 in housing 4 adjacent the open end thereof opposite to closure 30 receive a tubular bushing 40 that is in turn provided with an out-turned, annular flange 42 bearing tightly against the proximal end of housing 4. Bushing 40 is formed from a solid, non-compressible material which has a high dielectric constant, preferably ivory or non-magnetic material of like characteristics. Its external threads 44 terminate in spaced relationship to flange 42 whereby to present a tight intimate contact between bushing 40 and housing 4 at 46.

A collet 48 having a cylindrical bore 50 is telescoped within the bushing 40 and is split as at 52. The bushing 40 and the collet 48 are provided with complementary, frusto-conical, interengaging surfaces 56 and 58 respectively with the base end of collet 48 disposed exteriorly of flange 42.

In addition to head 20, mounting 22 includes an elongated, integral stem 60, threaded as at 62 remote from head 20, presenting an annular shoulder 64 of greater diameter than the inside diameter of bushing 40 adjacent the apex end thereof, but of less diameter than the inside diameter of housing 4.

Shoulder 64 faces outwardly toward nut 10 oppositely to an annular, internal shoulder 66 which it abuts and formed by the innermost end of bushing 40.

An internally tapped cup 68 threaded on stem 60 having wrench flats 70, receives the base end of collet 48 and has a continuous rim 72 thereon, circumscribing collet 48 and in sliding line contact with the proximal end of bushing 49.

It is noted that the apex end of collet 48 is spaced from shoulder 64 and that internally tapped lock nut 18 is carried by the outer end of stem 62 in tight engagement with cup 68.

Interconnected coil 12, conductors 14 and 16, 10 and mounting 22 are initially inserted into that end of housing 4 having threads 38 and the conductor 14 is joined to spring 18 exteriorly of housing 4 adjacent that end of the latter having threads 32.

Plug 28 is thereupon inserted in housing 4 to a point adjacent the inner end of threads 32 and the bushing 49 mounted in place with threads 38 and 44 preferably sealed by use of a suitable cement. Collet 22 is next positioned in place and the cup 68 mounted on stem 60. As the cup 68 is drawn tight, the rib 70 thereof slides easily on the bushing 49 while head 20 moves tightly against shoulder 66. Simultaneously, collet 48 wedges tightly in place to hold mounting 22 against rotation and to align the same coaxially with the longitudinal axis of housing 4. Thereupon, lock nut 18 is affixed to hold cup 68 against loosening.

The operator then retracts the plug 28 to properly position coil 12, locks the block 24 by means of screw 34, and places closure 30 in place within housing 4.

The speed of assembly and ease at which the same can be accomplished is now apparent. The tight fit at that end of housing 4 adjacent threads 38 and the rigid mounting of coil 12 thereto assures absolutely against the entrance of dust, dirt, moisture and other deleterious elements into housing 4.

Proper choosing of the materials for bushing 49 presents a holding means that will not yield to the compression that is exerted between head 20 and cup 68. And, by using substances for producing bushing 49 that will have high dielectric constant and a high resistance to corrosion and chemical damage, a highly efficient, fully satisfactory galvanometer is presented. After the mirror 37 and all associated parts are in place, mounting 22 will not be moved longitudinally by thrust created by tightening nut 68. The securing assembly above defined insures this result.

Further, bushing 49 is well reinforced not only by its surrounding housing 4, but by its contained collet 48 and stem 60. Even after considerable use, the mounting 22 can be easily and quickly removed with no damaging effect whatsoever to the remaining component parts of the instrument.

Having thus described the invention, what is claimed as new and desired to be secured by 60 Letters Patent is:

1. In a galvanometer, an elongated, hollow

housing provided with an open end; a tubular bushing secured within the housing, the innermost end of the bushing presenting a rigid, stationary shoulder facing inwardly away from said open end; an elongated coil mounting having a head on one end thereof within the housing and extending outwardly from the housing through said bushing; means carried by the mounting exteriorly of the housing for forcing said head tightly against the shoulder; and wedge structure in the bushing separate from the mounting and disposed for engagement by said means for aligning said mounting coaxially with the housing as the head is forced against the shoulder.

15 2. In a galvanometer, an elongated, hollow housing provided with an open end; a tubular bushing removably joined to the housing there-within, the innermost end of the bushing presenting a rigid, stationary shoulder facing inwardly away from said open end; a tubular, split collet in the bushing, said collet and said bushing having complementary, frusto-conical, interengaging surfaces; an elongated coil mounting having a head on one end thereof within the housing and extending outwardly from the housing through said collet; and means carried by the mounting exteriorly of the housing and bearing against the proximal ends of the bushing and the collet for forcing said head tightly against the shoulder and maintaining said collet in a position for aligning the mounting coaxially with the housing.

25 3. In a galvanometer, an elongated, hollow housing provided with an open end; structure presenting a frusto-conical surface in the housing and a stationary shoulder in the housing facing inwardly away from said open end; a shiftable, tubular collet in said housing, said collet having a surface complementary with and engaging said first-mentioned surface; an elongated coil mounting having a head on one end thereof within the housing and extending through said collet; and means carried by the mounting and bearing against one end of the collet remote from said head for forcing the latter tightly against the shoulder and maintaining the collet in a position for aligning the mounting coaxially with the housing.
